(57) **CLAIM**

The ornamental design for a cover for electronic device, as shown and described.

DESCRIPTION

FIG. 1 is a front perspective view of a cover for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view, in which the cover for electronic device is provided in an open position to illustrate an example environment; and,

FIG. 9 is a rear perspective view of FIG. 1.

The broken lines are for environmental purposes only and form no part of the claimed design.
